FIG. 2.

FIG. 3.

FIG. 4.

Inventor
S. H. Clark.

By *J. H. Murphy, Jr.* Attorney

UNITED STATES PATENT OFFICE.

SAMUEL HESS CLARK, OF KERMAN, CALIFORNIA.

COMBINED NEEDLE AND TWEEZERS.

Application filed January 6, 1921. Serial No. 435,445.

To all whom it may concern:

Be it known that I, SAMUEL HESS CLARK, a citizen of the United States, residing at Kerman, in the county of Fresno and State 5 of California, have invented certain new and useful Improvements in Combined Needles and Tweezers; and I do hereby declare the following to be a full, clear, and exact description of the invention, such as 10 will enable others skilled in the art to which it appertains to make and use the same.

This invention has relation to certain new and useful improvements in combined needles and tweezers, and has for its primary object the provision of a combination 15 device of this character which will be of simple and efficient construction, as well as inexpensive and easy to manufacture.

The invention has for another object the 20 provision of a combination device of the character stated in which the inner end of the needle will be carried by the member employed for pressing together or closing the jaws of the tweezers when the needle is 25 withdrawn to position between the jaws.

The invention has for a still further object the provision of a combination device of the character stated in which the connecting 30 ends of the jaws serve not only as the head or body of the device but also as a guide for the needle when the latter is extended and form the loop through which the suspending ring is engaged for suspending the device from a nail or the like when not in use.

With the foregoing and other objects in view as will appear as the description proceeds, the invention consists in the novel construction and arrangement of cooperating elements as hereinafter more specifically 35 set forth, claimed, and shown in the accompanying drawings forming a part of the present application and in which:

Figure 1 is an elevation with the needle extended;

Fig. 2 is a longitudinal section therethrough on the plane of line 2—2 of Fig. 1;

Fig. 3 is an elevation of the device at right angles to Fig. 1 and showing the needle in its withdrawn or innermost position; and

Fig. 4 is a transverse sectional view on the plane of line 4—4 of Fig. 3, looking in the direction indicated by the arrows.

Referring more in detail to the drawings, in which similar reference characters designate corresponding parts throughout the

several views, 1 designates the jaws of the tweezers which have reduced and beveled working ends as indicated by the numeral 2. These jaws 1 are formed of a strip of resilient metal or the like and which is bent intermediate its ends to form the round-ended or somewhat T-shaped head or body for the tweezers, as indicated by the numeral 3. The jaws 1 are curved from one another slightly, adjacent their working ends 2, and then turned toward one another so that the working ends may grip a sliver to extract the same from beneath the skin, or when the jaws 1 are employed for a similar purpose for which such devices are intended.

In order to draw together the jaws 1 and retain the same in closed or contacting position, that is, with their working ends contacting, I have provided a substantially rectangular jaw-encircling and closing ring 4 which is adapted to slide longitudinally upon the jaws 1, from the head 3, forwardly to a point past the longitudinal center of the jaws, at which point further forward movement of the ring 4 will be prevented by a stop rivet 5 or the like extended through one of the jaws 1, as clearly shown in the drawings.

A needle carrying block 6 is secured within the ring 4, between the jaws 1, by suitable securing members 7 extended through opposite portions or the side portions of the ring 4 as clearly shown in the drawings. The head of the needle 8 is secured in the block 6 and the point of the needle projects 85 slightly through the central opening 9 in the body portion 3 of the tweezers at the rear or inner end of the jaws 1, as also clearly shown in the drawings. When the ring 4 is moved toward the rear end or head or body 90 of the tweezers, the needle 8 is forced outwardly through the opening 9 provided therefor, and at the same time the jaws 1 separate. The sliding movement of the block 6 between the inner end portions of the 100 jaws 1 will also serve to force the jaws 1 outwardly or separate the same. A suitable ring 10 is extended through the looped or body portion 3 of the tweezers so that the device may be suspended on a suitable support, if desired, when not in use.

From the foregoing paragraphs taken in connection with the accompanying drawings, it will be evident that this combination tweezers and needle may be useful in many 110

cases, and the device is constructed in such a manner that there is clearly cooperation between the tweezers and the needle.

While the preferred embodiment of the invention has been shown and described, it will be understood that minor changes in the details of construction and arrangement of parts may be resorted to within the scope of what is claimed, without departing from the spirit of the invention.

What is claimed is:—

1. A combination device comprising tweezers, the tweezers including a body and gripping jaws, said body having a needle opening, and a ring slidably mounted on said jaws to draw together the latter, a block on said ring between said jaws, and a needle extending from said block and working through the opening of said body of the tweezers.

2. A combination device comprising tweezers including a head and gripping jaws extended therefrom, a ring slidably mounted on said jaws to draw together the latter when moved in one direction thereon, a block on said ring between said jaws, and a needle extending from said block and

adapted to be adjusted through the body of the tweezers by movement of said ring on said jaws.

3. A combination device comprising tweezers including a head having a central opening therein, jaws extended from said head and having their working ends turned toward one another and reduced, said working ends of the jaws being beveled on one face, a ring slidably mounted on said jaws, means for limiting movement of said ring in one direction, the head of the tweezers limiting movement of the ring in the opposite direction, a block on said ring between said jaws, a needle extending from said block and projecting through said head of the tweezers, said needle being adapted to be moved in either direction through said head of the tweezers upon movement of the ring on said jaws, and a suspending member secured through the head of the tweezers.

In testimony whereof I affix my signature in presence of two witnesses.

SAMUEL HESS CLARK.
